United States Patent Office

Des. 197,164
Patented Dec. 17, 1963

197,164

LUGGAGE HANDLE

Sol Koffler, 600 Blackstone Blvd., Providence, R.I.

Filed Aug. 7, 1963, Ser. No. 76,138

Term of patent 14 years

(Cl. D87—2)

Fig.1

Fig.2

Fig.3

Fig.6

Fig.4

Fig.5

I claim:

The ornamental design for a luggage handle, as shown.
